UNITED STATES PATENT OFFICE.

HERBERT A. CROSBY, OF STETTLER, ALBERTA, CANADA.

GOLD-SAVING DEVICE.

Application filed January 25, 1926. Serial No. 83,688.

This invention relates to apparatus used in the recovery of precious metals and has for its object the provision of a novel machine by means of which fine particles of gold or other precious metals may be recovered from sand, crushed ore and the like, the construction and arrangement being such that even particles of such fineness that they will float upon water will be recovered along with those of a heavier nature so that nothing of value will be lost.

Another object of the invention is to provide an apparatus of this character embodying a separator into which all the values are passed, the precious metal amalgamating with mercury and the tailings being discharged and carried to the dump.

A further object of the invention is to provide a mercury type separator involving or embodying a rapidly rotating muddler of peculiar construction which will agitate the water, sand and values mixed therewith entering the separator, the precious material being taken up by the mercury and the waste being thrown upwardly and outwardly by centrifugal force and discharged from the separator.

An additional object is to provide a device of this character which will be comparatively simple and inexpensive in manufacture, easy to operate, positive in action, efficient and durable in service, and a general improvement in the art.

With the above and other objects and advantages in view, the invention consists in the details of construction and arrangement of parts to be hereinafter more fully described and claimed, and illustrated in the accompanying drawings in which:

Figure 1 is a vertical section through the separator,

Figure 2 is a plan view of the separator bowl, and

Figure 3 is a vertical section through the separator bowl showing it moved to effect dumping.

Referring more particularly to the drawings, the numeral 33 designates the separator as a whole into the upper portion of which discharges a chute or spout 32 which conducts the mixture of water and values to be recovered from whatever preliminary treating machine or mechanism is used into the separator 33.

The device 33 is shown as including a casing 51 at the bottom of which is a support

52 having a concave partially spherical seat 53 supporting a partially spherical bowl 54 which is provided at its upper or open end with an outstanding flange 55 to which is bolted, at 56, an outstanding flange 57 on a tapered guide ring 58 above which is located a stationary cylinder 59 secured to the underside of the top of the casing 51 and provided at its lower end with a flange 60 engaged upon the flange 57 and held by the bolts 56. Leading from the upper portion of the cylinder 59 is a spout 61 leading to the discharge conveyor.

Located within and spaced from the walls of the cylinder 51 is a cylinder 62 supported as by means of brackets 63 secured to the underside of the top of the casing 51. The casing top is formed with an opening 64 leading into the inner cylinder 62 and receiving the discharge end of the chute 32. For centering the cylinder 62 with respect to the cylinder 59, I may provide screws 65 threaded through the latter and engaging the former. At its lower end, the cylinder 62 is tapered inwardly as shown at 66 and terminates in a constricted extension 67.

Located within and extending axially of the cylinder 62 is a shaft 68 rotated by any suitable means. At its lower end the shaft 68 carries a ball member 72 preferably concentric with and located within the bowl 54, the member 72 being held in place as by the transverse screw 73. The ball member 72 has a bore 74 therethrough rotatably engaged upon the extension 67 of the cylinder 62. The bowl is partly filled with mercury indicated at 75.

After the material to be separated has passed through whatever preliminary treatment is given the water carrying the material passes through the chute 32 into the cylinder 62 and through the bore 74 into the bowl 54. The particles of gold or other precious metal entering the bowl with the water, sand and other waste will amalgamate with the mercury 75 and owing to the rapid rotation of the ball 72 it is clear that the water and waste material will be thrown outwardly and will work its way up along the space between the outer and inner cylinders and be discharged through the spout 61 to the tailings dump. By removing the bolts 56 and performing other necessary operations the bowl may be tipped upon its seat 53 as shown in Figure 13 so that the amalgam may be poured out for subsequent

treatment to remove precious metal therefrom.

From the foregoing description and a study of the drawings it will be apparent that I have thus provided a simply constructed and rapidly operable mechanism whereby particles, no matter how small, of gold or other similar metals may be reclaimed. The device is adapted to operate continuously as the supply of material there-to may be made continuous. It is believed that the construction, operation and advantages will be readily apparent to one skilled in the art without further explanation.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

1. In a machine of the character described, a separator comprising a casing, a cylinder therein, a bowl connected with the cylinder and located therebelow, the cylinder having a discharge spout, said bowl containing mercury, an inner cylinder within said cylinder receiving material to be separated, a shaft journaled coaxially of said cylinders, and a partially spherical agitating member carried by the shaft and formed with an opening for the passage of material therethrough, the agitating member being located within said bowl.

2. A separator comprising a casing, a stationary cylinder therein, a partially spherical bowl member secured to the lower end of said cylinder and containing mercury, an inner cylinder spaced from the wall of said outer cylinder, a partially spherical agitating member carried by said second named cylinder, a shaft arranged axially of both cylinders and carrying said agitating member, the top of the second named cylinder being open, a spout leading into said open top, and a discharge spout leading from the first named cylinder and communicating with the space between the first and second named cylinders.

3. A separator for the purpose described, comprising a casing, a stationary cylinder mounted within the casing and depending from the top thereof, a partially spherical bowl member secured to the lower end of said stationary cylinder, a mass of mercury within said bowl member, an inner cylinder stationarily mounted within said first named cylinder in spaced relation to the walls thereof, the top of the casing having an

opening communicating with the second named cylinder, a spout leading into said opening and said second named cylinder, for conducting material thereinto, a discharge spout connected with the first named cylinder and communicating with the space between the first named and second named cylinders, a shaft journally mounted with respect to the casing and extending coaxially of the first and second named cylinders, said second named cylinder having a constricted lower end portion, a partially spherical agitating member carried by said shaft and rotatably mounted with respect to the first and second named cylinders and said bowl member and shaped to conformingly engage the constricted lower end portion of said second named cylinder, and screw means passing through the first named cylinder and engaging the second named cylinder for maintaining the latter in centered relation.

4. A separator for the purpose described, comprising a casing, a stationary cylinder mounted within the casing and depending from the top thereof, a partially spherical bowl member secured to the lower end of said stationary cylinder, a mass of mercury within said bowl member, an inner cylinder stationarily mounted within said first named cylinder in spaced relation to the walls thereof, the top of the casing having an opening communicating with the second named cylinder, a spout leading into said opening and said second named cylinder for conducting material thereinto, a discharge spout connected with the first named cylinder and communicating with the space between the first and second named cylinders, a shaft journally mounted with respect to the casing and extending coaxially of the first and second named cylinders, said second named cylinder having a constricted lower end portion, a partially spherical agitating member carried by said shaft and rotatably mounted with respect to the first and second named cylinders and said bowl member and shaped to conformingly engage the constricted lower end portion of the second named cylinder, and screw means passing through the first named cylinder and engaging the second named cylinder for maintaining the latter in centered relation, and screw means extending through said shaft and through said agitating member for maintaining the latter centered with respect to the shaft and to the constricted end portion of the second named cylinder.

In testimony whereof I affix my signature.

HERBERT A. CROSBY.
